Adam Hickman
Petters Patent

9253X

The Schedule referred to in these Petters Patent and making part of
the same containing a description in the words of the said Adam Hick-
man himself of his improvement in the spring saddle

To all to whom these presents shall come. Be it known that Adam
Hickman of the town of Abington in the County of Roanoke and
State of Virginia a citizen of the United States have invented a new
and useful improvement in the construction of the saddle tree and that
the description hereunto annexed and marked A. B. & C. is an exact descrip-
tion thereof as will be seen by the model of a saddle tree with any improve-
ment which accompanies this description. What I claim as my invention
and not previously known in the above described saddle tree is the spring
which is attached to the hind plating of the tree and then running to the un-
der part of the cantle and working on brass plates or steel fastened to the
upper part of the cantle as described in figure B. and the spring or
steel bars as described in figure A. and having the advantages de-
scribed in fig. A. Fig. A. represents a top view of the tree 142. on the
wooden bars of the tree fig. 3. is the cantle detached from wooden bars 142.
fig. B. are steel bars fastened by and working on hinges to the front plating
as the steel bars then running back are attached to the cantle by
several rivets b. b. Fig. B. represents a hinder view of the cantle with
the operating spring A. 1. being the cantle which as before mentioned in
fig. A is riveted to the steel bars 48. 5. A. 2. 2. are the wooden bars 3. 3.
the hind plating 3. 4. the operating spring A. 1. is fastened to the hind plating
3. 3. by rivets A. 2. the spring then running to the under part of the
cantle and working on steel plates fastened to the under part of the cantle
C. C. which spring gives the cantle & steel bars an action similar to
the operation of a bellows the saddle staff being drawn over the steel
bars. C. advantages. I do hereby certify that I have made three spring
saddles on the plan above delineated and from actual experience have

have ascertained that the plan is superior to any hitherto invented so far as my knowledge extends and will doubtless be of great utility to the public. Saddles made upon this plan are formed to combine the double advantage of ease both to the rider and horse. The spring gives ease to the rider however coarse or rough the gaits of the horse may be and at the same time preserves the horses back from galling or other injury.
